Primary Examiner — David G Muller(74) *Attorney, Agent, or Firm* — Panitch Schwarze Belisario & Nadel LLP(57) **CLAIM**

The ornamental design for a container lid, as shown and described.

DESCRIPTION

FIG. 1 is a front and top perspective view of a container lid in accordance with my new design;

FIG. 2 is a top plan view thereof;

FIG. 3 is a front elevational view thereof;

FIG. 4 is a rear elevational view thereof;

FIG. 5 is a right side elevational view thereof; and,

FIG. 6 is a left side elevational view thereof.

The broken lines in the figures are directed to environment, are for illustrative purposes only and form no part of the claimed design.

The bottom view of the container lid is not shown in the drawings nor described in the specification and, therefore, forms no part of the claimed design.
